(57) **CLAIM**

The ornamental design for a knee wrap, as shown and described.

DESCRIPTION

FIG. 1 is a first perspective view of a knee wrap showing my new design;

FIG. 2 is a second perspective view thereof;

FIG. 3 is a right-side elevation view thereof;

FIG. 4 is a left-side elevation view thereof;

FIG. 5 is a top plan view thereof;

FIG. 6 is a bottom plan view thereof; and

FIG. 7 is a back elevation thereof; and,

FIG. 8 is a front elevation view thereof, showing the knee wrap.

The broken lines in the drawings depict portions of the knee wrap that form no part of the claimed design.

1 Claim, 6 Drawing Sheets
